UNITED STATES PATENT OFFICE.

HERMAN LAWRENCE TURPIN, OF DALLAS, TEXAS.

RAIL-PLATE.

1,219,201.

Specification of Letters Patent. Patented Mar. 13, 1917.

Application filed September 15, 1916. Serial No. 120,285.

To all whom it may concern:

Be it known that I, HERMAN L. TURPIN, a citizen of the United States, residing at Dallas, in the county of Dallas and State of Texas, have invented certain useful Improvements in Rail-Plates, of which the following is a specification, reference being had therein to the accompanying drawing.

The invention relates to a rail joint, and 10 more particularly to the class of rail joint supports and fasteners.

The primary object of the invention is the provision of a rail joint of this character wherein the meeting ends of the rails 15 are firmly supported, so as to avoid either vertical, or lateral displacement, thereby eliminating the pounding of the car wheels when passing over the joint.

Another object of the invention is the 20 provision of a rail joint of this character wherein the rail ends are firmly and securely fastened in place, so as to avoid any possible displacement thereof, and also the fish plates or angle bars will be prevented from 25 springing or giving, due to heavy loads passing over the joint, and also, the rail ends will be materially reinforced to render maximum strength to the joint.

A further object of the invention is the 30 provision of a rail joint of this character wherein the angle bars or fish plates are securely fastened both to the rail ends and to the supporting plate for said rail ends, which plate is securely fastened upon the 35 ties, thereby eliminating any displacement of the rail ends, fish plates or angle bars, and supporting plate.

A still further object of the invention is the provision of a rail joint of this character 40 wherein the assemblage of the parts can be accomplished with despatch, for the uniting of the meeting ends of the rails for the support thereof, the support being designed to serve as a chair for the meeting ends of the 45 rails.

A still further object of the invention is the provision of a rail joint of this character which is simple in construction, strong, durable, thoroughly reliable, and efficient in 50 its purpose, and inexpensive in manufacture.

Other objects will be in part obvious and in part hereinafter pointed out.

The invention accordingly consists in the 55 features of construction, combination, and arrangement of parts hereinafter fully described, illustrated in the accompanying

drawing, and pointed out in the claim hereunto appended.

In the accompanying drawings:

Figure 1 is a fragmentary perspective view of a rail joint constructed in accordance with the invention.

Fig. 2 is a perspective view of the rail supporting plate.

Fig. 3 is a perspective view of one of the 65 fish plates or angle bars.

Fig. 4 is a fragmentary vertical transverse sectional view through the rail joint.

Similar reference characters indicate corresponding parts throughout the several 70 views in the drawing.

Referring to the drawings in detail, A and B designate the respective meeting ends of railway rails, which are of the ordinary well-known construction, and connected together by means of the rail joint herein-after fully described.

The rail joint comprises a main rail supporting plate or base 5, formed with a longitudinal medial thickened portion 6, provided with a flat face 7, upon which rests the bases of the meeting ends of the rails A and B, which are superimposed upon the supporting plate or base 5, as shown in Fig. 1 of the drawing, while at opposite sides of 85 the thickened portion 6 of said plate or base 5, are lateral outwardly inclined surfaces 8, for a purpose presently described.

The supporting plate or base 5, at its longer side edges is formed with upwardly 90 and inwardly bent locking or retaining flanges 9 for a pair of fish plates or angle bars 10, the vertical portions of which are formed on their inner faces with contacting ribs 11, adapted to fit against the webs of the 95 rail ends A and B, between the heads or balls and the bases of said rail ends, and laterally inclined portions, which fit against the correspondingly inclined surfaces of the bases of the rails A and B, these inclined portions 100 of the plates or bars 10 at opposite sides of the bases of the rails being formed on their under faces with thickened portions 12, the faces of which are correspondingly inclined to the inclined faces 8 at opposite sides of 105 the thickened portion 6 of the plate or base 5, so as to rest thereon, and in this manner, the laterally inclined portions of the plates or bars 10 serve as wedges in the supporting 110 plate or base 6.

It will be seen that when the fish plates or angle bars 10 are engaged in the support-

ing plate or base 5, the same will be securely locked thereon, and also the rail ends A and B will be firmly clamped and held against lateral displacement upon the flat surface 7 5 of the supporting base or plate 5.

Also, it will be obvious that there is no possibility of the working loose of the fish plates or angle bars 10, when locked in the supporting plate or base 5, which latter rests 10 upon the cross ties in the road bed.

Passed transversely at intervals through the vertical portions of the fish plates or angle bars 10, and the webs of the rails A and B are suitable fasteners 13, which unite 15 the rail ends and fish plates together, as is clearly shown in Fig. 1 of the drawing.

Formed or cut in the outer face of the vertical portion of each flange 9, at intervals thereof, are notches or rests 14, which extend 20 only partially through the depth of said flanges, and opening into each of these notches or rests 14, and through the bottom of the supporting plate, or base 5, are spike receiving openings or holes 15, through each 25 of which is passed the spike 16, which is driven into each cross tie for the fastening of the supporting base or plate thereon, the head of the spike 16 being seated within the notch or rest 14, when the said spike is 30 driven home into the notch, and in this manner the supporting plate or base 5 is securely fastened upon the cross ties.

The heads of the spikes 16 slightly protrude laterally without the notches or rests 14 when said heads are seated therein, so 35 that the spikes can be readily extracted from the tie when the occasion requires, as will be obvious.

From the foregoing, it is thought that the construction, and manner of operation of the 40 device will be clearly understood, and therefore, a more extended explanation has been omitted.

What is claimed is:

A rail joint comprising a supporting plate 45 having a medial thickened portion, provided with a flat face, upon which are adapted to rest the meeting ends of railway rails, upwardly and inwardly bent flanges at the longer edges of said supporting plate, a pair 50 of fish plates disposed at opposite sides of the rail ends, and locked in the flanges, means for fastening the fish plates to the rail ends, each fish plate having a thickened portion contacting with the supporting bases 55 between the flanges and the bases of the rail ends adjacent thereto, and spaced contacting ribs formed on the vertical portions of the fish plates, each flange being formed with spaced notches and holes intersecting the 60 same, and opening through the bottom of the supporting plates for receiving spikes.

In testimony whereof I affix my signature.
HERMAN LAWRENCE TURPIN.
